UNITED STATES PATENT OFFICE

157,553

FOOD CHOPPER

Herbert A. Wormeck and Frederick P. Hess, Philadelphia, Pa., assignors to The Enterprise Manufacturing Co., Philadelphia, Pa., a corporation of Pennsylvania

Application January 25, 1949, Serial No. 484

Term of patent 14 years

(Cl. D89—1)

To all whom it may concern:

Be it known that we, Herbert A. Wormeck and Frederick P. Hess, citizens of the United States, residing in Philadelphia, Philadelphia County, Pennsylvania, have invented a new, original, and ornamental Design for a Food Chopper, of which the following is a specification, reference being had to the accompanying drawings, forming a part thereof, in which:

Fig. 1 is a perspective view of a food chopper, showing our new design;

Fig. 2 is a similar perspective view of the opposite side thereof;

Fig. 3 is an end elevational view;

Fig. 4 is a plan view thereof; and

Fig. 5 is a side elevational view.

We claim:

The ornamental design for a food chopper, substantially as shown.

HERBERT A. WORMECK.
FREDERICK P. HESS.
